UNITED STATES PATENT OFFICE.

JOHN LARSON AND JAMES M. VAN SLYKE, OF MADISON, WISCONSIN.

DESIGN FOR A HANDLE FOR SPOONS, &c.

SPECIFICATION forming part of Design No. 21,855, dated September 13, 1892.

Application filed June 27, 1892. Serial No. 438,238. Term of patent 7 years.

To all whom it may concern:

Be it known that we, JOHN LARSON and JAMES M. VAN SLYKE, both citizens of the United States of America, residing in the city of Madison, county of Dane, and State of Wisconsin, have invented and produced a new and original Design for the Handles of Spoons and Similar Articles, of which the following is a specification, reference being had to the accompanying drawing, forming and hereby made a part thereof.

The said drawing is a view of the upper face of a spoon, showing our new design, and this view is all that we deem necessary fully to illustrate our said design.

The stem of the spoon is indicated in the drawing by the letters *d d* and is shown as a column or pillar.

The essential feature of our design is figures commemorative of the presidential campaign of the year 1892, and more particularly commemorative of Grover Cleveland.

The design consists in the shape and orna-

mentation shown in the drawing accompanying this specification.

The head of the handle (indicated by the letters *a a*) is a bust "in the round" of Grover Cleveland and is represented as standing upon a spread-eagle. (Indicated in the drawing aforesaid by the letters *b b*.) The spread-eagle above described rests at the point indicated in said drawing as *c c* upon the stem of the handle. (Shown in the drawing, as aforesaid, as *d d*.)

We claim as new—

The design for the handles of spoons or similar articles herein shown and described.

Witness our hands and seals, at Madison, in the State of Wisconsin, this 11th day of June, in the year of our Lord 1892.

JOHN LARSON. [L. S.]
JAMES M. VAN SLYKE. [L. S.]
